F. M. VENZIE

PARTITION AND LIKE BUILDING CONSTRUCTION

Filed Feb. 6, 1923

Patented Jan. 5, 1926.

1,568,110

UNITED STATES PATENT OFFICE.

FREDERICK M. VENZIE, OF PHILADELPHIA, PENNSYLVANIA.

PARTITION AND LIKE BUILDING CONSTRUCTION.

Application filed February 6, 1923. Serial No. 617,281.

To all whom it may concern:

Be it known that I, FREDERICK M. VENZIE, a citizen of the United States, residing at the city of Philadelphia, county of Philadelphia, and State of Pennsylvania, have invented a certain new and useful Improved Partition and like Building Construction, of which the following is a specification.

This invention, generally stated, relates to 10 building construction and has more particular relation to a partition, wall and ceiling structure calculated to receive a finishing coat of plaster.

The leading object of the present invention may be said to reside in the providing 15 of a structure of the character stated in which is combined efficiency, cheapness, lightness of material and sound and fire-proof characteristics. A further object resides in the provision of general details of 20 construction and in the arrangement, combination and connection of parts for attaining the results sought by the leading object. A still further object resides in the provision 25 of a novel form of unit of block-like or slab contour possessed of lightness, and fire and sound-proof characteristics adapted for arrangement between and for attachment to metallic supporting strips. A still further 30 object resides in the provision of a novel form of clip for attaching said units to said supporting strips. Still another object resides in the provision of anchoring means whereby end units may be supported with 35 respect to a supporting strip in the event that a door-way, window or like opening is required, at which place the usual clip I employ is not desirable. Other and further objects not at this time more fully explained 40 will appear hereinafter.

The invention consists of the improvements hereinafter described and finally claimed.

The nature, characteristic features and 45 scope of the invention will be more fully understood from the following description taken in connection with the accompanying drawings forming part hereof, and in which:

50 Fig. 1, is a fragmentary view of a wall or partition embodying features of the invention.

Fig. 2, is a sectional plan view of the parts shown in Fig. 1.

55 Fig. 3, is a sectional end view of the parts shown in Fig. 1.

Fig. 4, is a face view of one of the slab-units detached.

Fig. 5, illustrates one of the clips detached, and

Fig. 6, is a plan view of one of the anchors detached.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously 65 arranged and organized and that my invention is not limited to the precise arrangement and organization of the instrumentalities as herein shown and described.

Generally stated the invention consists of 70 a unit or slab construction which may be secured directly to a wooden or other partition or wall to render the same sound and fire-proof or which may be built up to itself 75 form a wall, partition or ceiling. In the last mentioned construction special and 80 novel clips and anchors are required which also form part of the present invention. A description will first be given of the unit 85 construction. Each unit is of rectangular, slab-like contour and is designated 10. One 90 face of a unit 10 is beveled as at 11 along all four edges as clearly shown in Fig. 4. The beveled portions are each grooved as at 12 the grooves being in communication to form 95 a continuous channel the purpose of which will presently appear. Each slab is hollow 100 and is formed of refractory material. In practice good results have been obtained by using a mixture composed of plaster, asbestos and burlap. Within each slab is contained felt a preferably in compacted or slab form. The walls of the unit 10 are relatively thin in cross-section whilst the felt is of relatively thick cross-section, see Fig.

105 3. While the formation of unit with felt therein may be accomplished in different ways the arrangement shown in the drawings will serve for illustrative purposes. The unit may be made in two pieces of which one is dished to receive the felt and the other comprised of a lid or cover which may be pressed against the felt and caused to adhere to the unit and felt by means of an adhesive as glue. Such a unit is of very 110 light construction weighing considerably less than tiles and similar building commodi-

ties and is sound and fire-proof. One way of utilizing such units is to place same upon a wooden partition positioned end to end and secured as by nails with the beveled faces of the units exposed. A coat or coats of suitable material as plaster and asbestos is then applied to the exposed unit faces, said material filling the V-shaped spaces between adjacent units as well as filling the 10 grooves 12 thereby forming an efficient interlock. Thus a wooden partition may be readily made sound and fire-proof by applying units upon each side thereof.

A description will now be given of the 15 manner of constructing a partition, wall or ceiling in which the units constitute the entire structure use being made of metallic supporting strips, clips and anchors for maintaining the units in proper position and 20 for illustrative purposes a description will be given of the manner of erecting a partition as is disclosed in Fig. 1. Secured to the floor 13 as by screws or nails are spaced, vertically disposed, metal supporting strips 25 14 of a height in accordance with the partition being formed. A unit is of the approximate width of the space between adjacent strips and said units are positioned therebetween, end to end with the lowermost of the units resting upon floor 13. For 30 the purpose of retaining the units in position between strips 14 use is made of clips such as shown in Fig. 5. These clips are stamped from metal and each consist of a body 15 35 one end of which is slotted as at 16 and the opposite end of which is provided with oppositely disposed wings 17-17 arranged at right angles to the body 15. That end of the body 15 provided with the wings 17-17 40 has bent out therefrom extended in parallelism with said body a supporting strip engaging member 18 the free end of which is provided with a hook 19. In practice after the strips 14 are secured to place a plurality 45 of the above described clips are positioned upon said strips by engaging parts 18-19 of a clip around one face of a strip with the body part 15 of a clip abutting against the other face of a strip 14. Each clip is interlocked with respect to a strip 14 by means 50 of a plate 20 slotted as at 21, the slotted part 21 being caused to engage with the slot 16 of body 15 with plate 20 paralleling wings 17-17. The combined plate and wings form 55 opposed U-shaped sockets to accommodate and retain in position the units 10. The units 10 may be tied together at their meeting edges by other clips and locking plates similar in all respects to clips above described except that no strip engaging hooks 60 are required. These additional clips are best seen in Figs. 1 and 3 in which the body part is designated 15', the wings 17' and the locking plate 20'.

65 In the event that a doorway or other open-

ing is desired in a partition being erected the clips are omitted upon a strip 14' facing such opening, see right hand side of Fig. 1. In order to maintain units 10 in position adjacent a strip 14' use is made of anchors 22 70 see Fig. 6. Each anchor comprises a thin metal band of a length to engage around a strip 14 and a strip 14' see Fig. 1, the ends of such band being split and bent inwardly in spaced, parallel, strip engaging prongs 75 23-24 of which prong 24 is hook-shaped as at 25 to engage around the edge of a strip.

The partition is now ready to receive one or more coats of suitable finishing material 26. In practice good results are obtained by 80 using a plaster and asbestos mixture. This finishing material may be of any refractory composition thus adding to the fire-proofing qualities of the work being done. The material 26 enters the V-shaped spaces between 85 adjacent units as well as the grooves 12 of the units thus providing an interlock of parts which is desirable.

It will now be apparent that I have devised a novel and useful construction which 90 embodies the features of advantage enumerated as desirable in the statement of the invention and the above description and while I have in the present instance shown and 95 described the preferred embodiment thereof which has been found in practice to give satisfactory and reliable results, it is to be understood that the same is susceptible of modification in various particulars without departing from the spirit or scope of the 100 invention or sacrificing any of its advantages.

What I claim is:

1. A construction of the character stated comprising spaced and fixed supporting strips arranged in parallelism, a plurality of spaced clips detachably engaging said strips each clip forming opposed U-shaped unit accommodating sockets, a plurality of units comprised of blocks of fire-proofing material of a width approximating the distance edgewise between the U-shaped portion of adjacent strips fitted between pairs of strips end to end and engaging in said sockets and a fire-proofing surfacing material applied to the opposite faces of said 115 units.

2. A construction as described in claim 1, characterized by each of said units having bevelled and grooved marginal portions upon one face thereof adjacent bevelled portions of said units forming V-shaped depressions in which depressions and grooves said surfacing material is received thereby forming an interlock of parts.

3. A construction as described in claim 1, characterized by vertically disposed clips for tying together abutting upper and lower ends of said units.

4. A construction as described in claim 1, characterized by certain of said units being 130

maintained in position by means of anchors connected between a pair of said supporting strip each anchor being comprised of a band the ends of which are shaped to engage 5 around said strips.

5. A construction as described in claim 1, characterized by said units being of hollow construction and filled with sound proofing material.

10. 6. In a construction of the character stated a unit comprised of a hollow slab of fire-proofing material having bevelled and grooved marginal portions upon one face

thereof said slab being adapted to be filled with a fire-proofing material of a character 15 differing from the slab material.

7. In a construction of the character stated a unit comprised of a hollow slab of plaster, asbestos and burlap said slab having bevelled and grooved marginal portions upon one 20 face thereof said slab being adapted to be filled with felt or equivalent sound proofing material.

In testimony whereof, I have hereunto signed my name.

FREDERICK M. VENZIE.
